UNITED STATES PATENT OFFICE

JOSEPH D. LASATER, OF SULPHUR SPRINGS, TEXAS, ASSIGNOR OF ONE-THIRD TO JOHN D. WILLIAMS, OF SULPHUR SPRINGS, TEXAS

REGISTER FOR LIQUID-DISPENSING APPARATUS

Application filed June 8, 1929. Serial No. 369,442.

This invention is an apparatus for indicating when a predetermined quantity of liquid has been drawn from a dispensing apparatus. The invention is designed more particularly for use in connection with the pumps for dispensing gasoline, and has for its object the provision of an apparatus operated by the flow of the gasoline through the outlet nozzle to sound an alarm or otherwise signalize the passing of the predetermined quantity. The invention provides means whereby the alarm may be set to sound when any desired quantity has been drawn and the apparatus may be employed in various ways. The invention is illustrated in the accompanying drawings and will be hereinafter first fully described and then more particularly pointed out in the appended claims.

In the drawings:

20 Figure 1 is a front elevation of the device showing the same connected with the outlet nozzle of a gasoline dispensing pump,

Fig. 2 is a rear elevation of the same,

25 Fig. 3 is a view, partly in plan and partly in horizontal section, on the line 3-3 of Fig. 1,

Figs. 4, 5 and 6 are vertical sections taken on the lines 4-4, 5-5, 6-6, respectively, in

30 Fig. 8,

Fig. 7 is a detail elevation of the main ratchet wheel and the device for checking rebound of the same,

Fig. 8 is a sectional elevation on the line 8-8 of Fig. 7,

35 Fig. 9 is a plan view of the circuit closer mounted on the discharge nozzle with the top of the casing removed,

Fig. 10 is a longitudinal section on the line 10-10 of Fig. 9,

40 Fig. 11 is a detail.

Fig. 12 is a view similar to Fig. 4 with the parts in a different position.

Fig. 13 is a detail elevation of a trip device,

45 Fig. 14 is an end elevation of the structure shown in Figs. 9 and 10, and

Fig. 15 is a diagram.

In the drawings, the reference numeral 1 indicates a casing which may be mounted at any convenient point and is equipped with

a hinged door 2 whereby the mechanism may be secured against tampering when so desired. The outlet nozzle of the dispensing pump is indicated at 3, a hose 4 being coupled to the nozzle in the usual manner.

55 In carrying out the present invention, there is provided within the nozzle 3 a shaft 5 extending axially of the nozzle and journaled in bearings provided therefor in a suitable frame 6 secured within the nozzle. Upon this shaft 5 between the ends of the frame 6 is secured a worm or screw 7 which is of such diameter that it extends to the peripheral wall of the frame and must, therefore, if unrestrained, be actuated by the gasoline flowing through the nozzle. One end of the shaft 5 is equipped with a crank 8 and a wrist pin 9 disposed eccentrically upon the crank, and adjacent said end of the shaft a bearing sleeve 10 is fitted through and secured in the wall of the nozzle, a rock shaft 11 extending axially through said bearing sleeve and being journaled therein. To the lower end of the shaft 11 is secured a crank 12 having a pin 13 depending from its free end in the path of the wrist pin 9, as shown clearly in Fig. 10, a collar 100 being fitted around the shaft between the crank 12 and the end of the bearing sleeve to prevent leakage through the sleeve. At the opposite end of the worm is a lug 101 which plays between quadrantly spaced stops 102 on the frame 6 and thereby limits the movement of the shaft to one-quarter of a revolution. Upon the nozzle is secured a casing 14 into one end of which the bearing sleeve 10 extends, and intermediate the height of this casing 14 is secured a shelf or partition 15 of fiber or other insulating material. Secured upon the shelf 15 adjacent one end thereof are brackets 16 to which are secured resilient contact fingers 17 and 18 which extend longitudinally of the shelf and are normally spaced apart, as shown in Fig. 9. Electric conductors 19 lead through an opening 20 in the top 21 of the casing 14 and are secured to binding posts 22 on the respective brackets 16. The contact fingers 17 and 18 are equipped with opposed lugs 23 at their free ends and the finger 18 is extended beyond said lug and then bent laterally, as shown at 24,

to provide an abutment in the path of a cam or crank 25 secured on the upper end of the shaft 11, as shown and as will be understood. A spring 26 is secured upon the shelf 15 and exerts an upward tension on the crank 25 to hold the collar 100 to the end of the bearing sleeve and eliminate leakage. The extension 24 of the finger 18 acts as a spring on the crank 25 to return the same to normal inactive position, and stop pins 27, arranged adjacent the respective contact fingers, serve to limit the movement thereof in an obvious manner. The conductors 19 are brought to the casing 14 through a cable 28 which leads from binding posts 29 and 30 within the casing 1 so that a shunt circuit is formed including the parts just described.

When the machine is idle, the circuit will be broken and the contacts will be separated, as shown in Fig. 9. When, however, the machine is operating and gasoline is flowing through the outlet nozzle, the worm 7 will be given a quarter turn by the initial impact of the fluid so that the wrist pin 9 will be rocked to bear against the pendent pin 13 and rock the crank 12, causing the shaft 11 to turn and the crank or eccentric 25 to press the contact finger 18 toward the contact finger 17 and bring the spaced lugs 23 into contact. The circuit through the motor will be thereby completed and the registering apparatus will operate. When the flow ceases, the parts are restored to initial position under the influence of the spring extension 24, as before stated. It must be understood that the resiliency of the fingers 17 and 18 tends to constantly hold them apart and is sufficient to separate them as long as no liquid is flowing through the nozzle 4, under which conditions the lug 101 on the screw 7 will rest against the upper stop 102 and the wrist pin 9 will be held in position to instantly actuate the pin 13 and shaft 11 when liquid flows. When liquid flows through the nozzle, the pressure of the liquid upon the screw 7 will rock the screw and the shaft 5 to the position shown in Fig. 14 with the lug 101 against the lower stop 102, thereby closing the circuit through the contact lugs 23, as described, and as long as the liquid flows its pressure will hold the parts in the stated position, the pressure upon the screw blade or vane acting in opposition to the springs 17 and 18.

The current for operating the apparatus may be supplied from any convenient socket and, to that end, a cable 31 is provided equipped with the usual plug 32 and carrying conductors secured to the binding posts 33 and 34, respectively. The binding posts 29, 30, 33 and 34 are secured upon a block 35 of insulation secured to one side of a frame 36 which is secured within the casing 1. The several binding posts extend through metal caps or plates 37 and the posts 29 and 33 pass through the same plate so that they are elec-

trically connected. A conductor 38 leads from the lowest plate 37 to one side of the motor 39 which is an electro-magnet mounted upon the frame 36 and cooperating with an armature 40. From the uppermost plate 37, a conductor 41 leads to the opposite side of the motor and conductors 42 lead from the uppermost and intermediate plates 37 respectively to binding posts 43 at the back of the casing and the frame from which resilient contact fingers 44 rise, said fingers being equipped with lugs 45 similar to the lugs 23, previously described. It will be understood that the wires 38, 41 and 42 are soldered or otherwise intimately united to the respective plates 37. One finger 44 extends above the other finger into the path of a slideable and rockable rod 46 which is mounted upon the back of the frame and carries a hammer or clapper 47 which is adapted to sound a bell 48 when actuated. The rod 46 is moved in one direction by a spring 49 to break the circuit and is moved in the opposite direction to close the circuit by a crank arm 50.

The armature 40 is resiliently supported upon a post 103 by leaf springs 51 at one end and adjacent its opposite end a spring plate 52 rises therefrom to connect it to one end of a lever 53 which has its opposite end pivotally mounted upon a shaft 54 mounted within the frame 36. Carried by the lever 53 is a friction block or shoe 55, and springs 56 attached to said shoe and the lever normally hold the shoe to the lever in the raised position, the armature being vibrated when the magnet is energized so that the lever will be rocked. It should be stated at this point that the motor I have employed operates only on alternating current, the current most generally available being 110 volts, 60 cycle A. C. This current stops and starts, so to speak, sixty times a second and the armature is accordingly attracted and released sixty times a second, vibrating very rapidly. The shoe or block 55 is of a somewhat eccentric form and a roller 57, carried by the lever, bears upon the shoe so that upon the downward stroke of the lever the shoe will be caused to bind against a driving wheel 58 secured upon the shaft 54 and thereby actuate said shaft. The wheel preferably has a grooved periphery, as shown at 59, and the shoe has a wedge-shaped edge, as shown at 60, so as to make an effectual binding engagement. Upon the up stroke of the lever, the shoe will be disengaged from the driving pulley or wheel but the wheel will continue to rotate under the influence of a heavy flywheel 61 secured upon the shaft 54 immediately adjacent the wheel, as shown clearly in Fig. 3. An adjusting rod 62 is secured to the springs 51 and rises therefrom between the pulley 58 and the flywheel 61 to be engaged by a set screw 63 in the top of the casing so that the tension of the springs

may be adjusted and the action of the armature 40 thereby nicely regulated.

Upon the shaft 54, at the front end thereof, is secured a pinion 64 meshing with a gear 65 carried by a shaft mounted adjacent the front end of the shaft 54, as will be understood. The gear 65 has a wrist pin 66 which is arranged to engage the teeth 67 of the main ratchet wheel 68 and impart a step by step movement to said wheel. A spring-pressed dog 69 is mounted in the frame adjacent the gear 65 and engages the teeth 67 to prevent retrograde movement of the ratchet wheel, as will be understood upon reference to Fig. 4. The ratchet wheel 68 carries an eccentric pin or stud 70 which is adapted to engage a stop member set according to the time the apparatus is to run. On the rear side of the ratchet wheel 68 are spaced pins or studs 71 forming a circular series extending entirely around the wheel and these pins engage an escapement to prevent rebound of the ratchet wheel. The escapement consists of a lever 72 pivoted at its lower end to the frame and having a tooth 73 at its upper end. A bridge piece 74 extends from the lever below said tooth inwardly with respect to the wheel 68 and is of offset formation so that it will clear the pins 71, as will be understood upon reference to Figs. 7 and 8. Carried by and rising from the bridge piece 74 is a post 104 having a pair of teeth 75 which are opposed to the tooth 73 and disposed in staggered relation thereto so that the teeth will alternately engage the pins 71 and eliminate rebound of the wheel when it is actuated. A leaf spring 90 disposed between the post 104 and the rear side of the wheel 68 functions as an anti-rattler, and a volute spring 91 having its ends secured to the frame and the hub of the wheel 68, respectively, moves the wheel toward the zero position.

Disposed coaxially with the ratchet wheel 68 at the front of the frame is a dial 76 which may be calibrated in any desired manner and, of course, is intended to have each graduation represent one gallon of the liquid being dispensed. A pointer 77 is arranged in front of the dial 76 and is set by manipulation of a nut or knob 78 which locks the pointer on its shaft, a spacer 79 being disposed between the pointer and the dial. A stop pin 80 projects from the face of the dial near the top thereof and immediately adjacent the zero point of the scale to limit the movement of the pointer. Fixed to the rear end of the shaft or pivot 81 upon which the pointer is secured is a collar 105 upon which is pivoted the stop member or dog 82 which is set at any desired point in the path of the stud 70 by the manipulation of the pointer so that when the ratchet wheel has been rotated through the predetermined arc the pin 70 will impinge against the dog 82 and thereby activate devices which will cause the bell 48 to be sounded. The

dog 82 has a two-armed body pivoted to the collar 105 at the junction of the arms, as at 106, one arm being straight and extending beyond the periphery of the collar and the other arm being arcuate and lying within the area of the collar, as shown in Fig. 13. The free end of the arcuate arm is provided with a lateral terminal lug 107 and a spring 108 presses said arm and lug toward the pointer pivot or shaft 81, a stop pin or lug 109 being provided on the collar to limit the movement of the arm under the influence of the spring. Upon the straight arm of the dog is pivoted an extension 110 having a back plate 111 adapted to bear against the edge of the arm and yieldably held to the arm by a spring 112 coiled around the pivot and having one end engaged with the arm and its opposite end bearing upon a lug 113 on the extension. By reason of this arrangement, if the pin 70 engages the back of the extension, the dog and the pin will move in unison, but if the pin engages the front of the extension the extension will yield and the pin ride past the same. The rear end of the shaft 81 is hollow and receives the front end of the axle or shaft 114 upon which ratchet wheel 68 is secured, the two shafts being axially alined. Loosely mounted upon the axle or shaft 114 is a grooved collar 83 in which is engaged a fork 84 upon the inner end of a lever 85 fulcrumed in a bracket 86 upon the frame and having its upper end hooked and turned laterally, as shown at 87, and also formed with a cam 115 arranged to ride against the pawl 69 and release the same, the hook 87 assuming a position above the pawl to prevent its being thrown violently outwardly to a position from which it will not readily return to engage the ratchet wheel. A spring 88 bears against the upper end of the lever 85 and the lug 107 on the dog 82 normally is disposed between the sleeve 83 and the back of the dial to hold the sleeve toward the ratchet wheel 68. When the dog 82 is rocked, the lug 107 is moved beyond the circumference of the sleeve, whereupon the spring 88 expands and rocks the lever 85, causing the cam 115 to disengage the pawl 69 from the wheel 68. The spring 91, which was wound by the step by step rotation of the wheel, then at once unwinds and turns the wheel in the reverse direction, setting it at zero before the gear 65 has made a complete revolution.

The ratchet teeth of the wheel 68 are interrupted at one point, as shown at 89, to constitute a safety device, the rotation of the wheel and the operation of the machine being stopped whenever the pin 66 on the driving gear engages the notch or blank 89. If the pointer should be set at 25, for instance, and, after the machine has started to operate, the pointer should be thrown back to 10, the machine would not give a signal when

4

twenty-five gallons had passed through the nozzle but would continue to count gallons until the pin 66 met the space 89 when the ratchet wheel would stop. To correct this trouble, the pointer is turned to the right until it strikes the pin 80 and then turned back to the graduation 88 at which point the signal will be operated. The pointer may then be set at any desired graduation and the machine will operate properly.

In addition to the trip pin 70, a stop pin 92 projects from the front side of the main ratchet wheel 68, and this pin arrests the return movement of the ratchet wheel by impinging against the lower end of a bracket or arm 93 which depends from the top of the frame 36. A latch 94 is pivoted on and depends below the bracket 93 and its lower end is held to the path of the pin 92 by a spring 95. Near its lower end, the latch is formed with a cam shoulder 96 on its edge presented to the pin 92, and above said cam on the same edge is a ledge or shoulder 97 from the tip of which an inclined surface 98 extends downwardly to merge into the edge of the latch. A rocking arm 99 is disposed between the latch and the bracket 93 and is equipped with a lateral lug 116 which bears against the edge of the latch and, at times, rests on the ledge 97. The free end of the arm 99 has vertically spaced lugs 117 between which is a lug 118 on the bracket 93, and an additional lug 119 on the bracket above the arm limits the upward movement thereof. The arm 99 is secured on a rock shaft 120 which extends from front to rear of the frame and upon the rear end of which the previously mentioned crank 50 is secured. Near the end of the rocking slide 46, an arm 121 is fixed thereon and projects forward therefrom to engage over a hook 122 depending from the free end of the armature, a spring 123 secured in the frame and projecting under the arm preventing rattling and tending constantly to lift the free end above the bill of the hook so that it will engage easily thereover when the slide 46 is shifted endwise by the crank 50, and a stop 124 being provided on the frame to prevent the arm 121 dropping so far that it cannot engage over the hook 122.

The machine measures by time, one gallon flowing through the delivery nozzle every time the main ratchet wheel is fed forward one tooth, and the parts being adjusted so that the wheel is fed forward one step every four seconds which is the period usually required for the flow of one gallon of gasoline. One method of using the machine is to set the pointer at the graduation indicating the quantity desired by the customer, in which event the signal will be sounded when the indicated quantity has been delivered. The machine is designed principally, however, for use in promoting sales at a gasoline station

for which purpose the indicator may be set at one of the larger numbers, say 75, and an extra gallon given free to the customer who buys the seventy-fifth gallon. The signal will announce the passing of the seventy-fifth gallon and will not be actuated until the seventy-fifth gallon has passed, whereupon the then customer will be thereby informed that he is entitled to one free gallon.

The ratchet wheel 68 is fed forward until the pin 70 impinges upon the dog 82 and releases the sleeve 83, as stated, whereupon the spring 91 at once rotates the wheel in the opposite direction until the pin 92 comes into contact with the bracket 93. As the pin 92 approaches the bracket, it will ride upon the lower portion of the latch 94 and push the same aside to facilitate movement of the arm 99, then impinge against the lower edge of the arm 99 and rock the same upwardly so that just as the pin engages the bracket 93 it will be free of the latch and the pin 116 will be above the shoulder 97, whereupon the latch swings under the influence of the spring 95 to engage the shoulder 97 under the pin 116 and thereby hold the arm 99 in the raised position. When the arm 99 is swung upwardly, the shaft 120 is rocked and the crank 50 caused to push the slide 46 to close the circuit through the contact lugs 45, whereupon the bell will ring and will continue to ring until the pin 92 is moved downwardly or the circuit through the motor is broken. Upon downward movement of the pin 92, the pin will ride upon the cam shoulder 96 of the latch and push the latch aside so as to release the arm 99 which will thereupon swing downward and impart reverse movement to the crank 50, permitting the contact lugs 45 to separate.

When the shunt circuit is closed through the conductors 19 by the coming together of the contacts 23, the current flows through one wire of the cable 31 to the post 34 and thence through the lowest plate 37 and wire 38 to one side of the magnet or motor. From the motor, the current flows through wire 41 to the top plate 37 thence through the shunt conductors 19 and central plate 37 to post 33 whence it passes through cable 31 to the source. When the contacts 45 are brought together by the described action of the slide 46, one side of the circuit will be, as before, through the post 34 and wire 38 to one side of the motor and from the opposite side of the motor through the wire 41 to the top plate 37. The current then flows over the upper wire 42 and its post 43 to and through the fingers 44 and contacts 45 and thence through the lower wire 42 to the central plate 37 whence it passes through the cable 31 to the source. Thus, there will be a circuit through the motor even though the first-formed shunt circuit be broken by the stoppage of the flow of gasoline and the bell

will be sounded until the descent of the pin 92 permits the shaft 120 to rock and swing the crank 50 in a direction away from the contacts 45, whereupon the contacts will separate. It will be understood that when the bell circuit is closed through the motor the armature will vibrate and as the arm 121 is then resting on the hook 122 at the end of the armature, the rod 46 will be rocked and the hammer 47 caused to play on the bell.

The position of the dog 82 corresponds to the position of the pointer 77. If the pointer be set at 75 on the dial and then moved back 15 to 1 before seventy-five gallons have been delivered, the sounding of the bell will not truly indicate the delivery of seventy-five gallons. When the pointer is moved back to 1, as suggested, the extension 110 will be carried 20 past the pin 70 and if the pin 66 happens to be engaged in the teeth of the wheel 68, the machine will not trip. If, however, the pin 66 happens to be not engaged with the teeth of the wheel 68, the machine will trip 25 and the bell will be sounded. If the pin 66 is engaged, the machine will not trip and if the pointer be left on 1, the wheel 68 will continue to operate until the pin 66 engages in the vacant space or notch 89, whereupon 30 the wheel 68 will stop but the wheel 65 may continue to rotate, the pin 66 merely engaging in the notch 89 at each rotation of the gear wheel. To restore the machine to accurate working condition, the pointer is 35 moved clockwise until it impinges against the stop pin 80 and is then moved back to the graduation 88 on the dial, thereby bringing the dog 82 into contact with the trip pin 70, whereupon the lever 85 will be rocked 40 and the pawl 69 released, as previously described. The wheel 68 will then return to zero and sound the bell. The pointer may then be again set at 75 and the wheel 68 may be restored to the position it occupied 45 before being disturbed by temporarily disconnecting the conductors 19 and bridging the posts 29 and 30.

When the machine is tripped and the lever 50 85 rocked, as previously described, to release the dog 69 from the wheel 68, the lever is held in such tripped position until the shunt circuit is again closed, whereupon the driving wheel 65 will be rotated and the pin 66, of course, caused to travel with the wheel. 55 The pin 66 will then be caused to ride against the deflected hook 87 at the upper end of the lever 85 and rock the lever so that the collar or sleeve 83 will be slid away from the dog 82 to its initial or normal position and the 60 spring 108 will act upon the dog so as to throw it into the position between the sleeve and the disk 105, thereby restoring the parts to the first described position.

Having thus described the invention, I 65 claim:

1. Means for measuring a liquid including a conduit through which the liquid may flow, an impeller arranged within the conduit and having an eccentric wrist pin, a pair of contact fingers arranged upon the conduit, one of said fingers being extended beyond the other finger and formed into an abutment, a rock shaft mounted in the wall of the conduit and provided at its upper end with a crank engaging said abutment and at its lower end with a crank arranged in the path of the wrist pin, a signal, and an electric circuit including the signal and said contact fingers whereby the signal will be energized at the end of a predetermined interval. 70

2. Means for measuring a liquid comprising a dial, a pointer cooperating with the dial, a stop connected with the pointer to be set thereby, a wheel arranged coaxially with the dial, a pin projecting therefrom into a path including the stop whereby to engage the stop and arrest the movement of the wheel, means for intermittently moving the wheel, and means controlled by flow of the liquid for driving the last-mentioned means. 80

3. Means for measuring a liquid including a measuring wheel, a stop mechanism having one member mounted on the wheel and another member in the path of said member on the wheel, a vibratory electric motor, means controlled by the flow of the liquid for energizing said motor, gearing driven by the motor for intermittently rotating the indicator wheel, and means activated by the stop mechanism for rendering said gearing inactive and permitting reverse movement of the wheel. 100

4. Means for measuring a liquid including a signal, an electric circuit for operating the signal, a control wheel, means controlled by the flow of the liquid to intermittently move said wheel in one direction, means for rendering said means inactive at a predetermined point in the rotation of the wheel, means for imparting reverse movement to the wheel, and means controlled by the reverse movement of the wheel for activating the signal. 110

5. In means for measuring a liquid, an electromagnet, means controlled by the flow of the liquid for energizing said magnet, a vibratory armature for the magnet, a driving wheel, a lever pivoted concentric with said driving wheel, connections between the lever and the armature, and a shoe carried by the lever and adapted to frictionally engage the driving wheel upon movement of the lever in one direction. 115

6. In means for measuring a liquid, a driving wheel, a lever pivoted concentric with said wheel, a flywheel connected coaxially with the driving wheel, a shoe arranged eccentric to the lever and carried thereby, a yieldable support for the shoe on the lever, 120

- and means for vibrating the lever whereby upon one stroke of the lever the driving wheel will be actuated by the shoe and upon the other stroke of the lever the shoe will be free of the driving wheel.
7. In means for measuring a liquid, a driving wheel, a lever mounted concentrically therewith, electro-magnetic means for vibrating the lever, and a shoe yieldably supported by the lever in position to engage the wheel whereby upon movement of the lever in one direction the driving wheel will be actuated and upon movement in the other direction the shoe will be free of the wheel.
15. 8. In apparatus for the purpose set forth, a conduit through which a liquid may flow, a shaft mounted axially in the conduit, a spiral blade on said shaft, stops on the inner wall of the conduit spaced circumferentially thereof, a cooperating projection on the blade between the stops to limit the turning of the blade and the shaft, and an electric circuit opened and closed by the turning of the blade and shaft.
25. 9. In apparatus for the purpose set forth, a control wheel, means controlled by the flow of a liquid for rotating the wheel, a dial coaxial with the wheel, a pointer movable over the dial, a dog movable with the pointer and mounted for rocking movement relative to the pointer, a projection on the wheel adapted to engage and rock the dog, and means whereby upon rocking the dog reverse rotation of the wheel will be effected.
35. 10. In apparatus, for the purpose set forth, a main ratchet wheel, means controlled by the flow of a liquid to impart a step by step rotation to the wheel, a pawl normally engaging the wheel to prevent reverse movement thereof, a projection on the wheel, a shiftable dog in the path of said projection, means for imparting reverse rotation to the wheel, and a rocking arm having one end engaged with the shiftable dog and its opposite end provided with a cam arrangement to ride under the pawl whereby upon engagement of the dog by the projection the pawl will be released and reverse rotation of the wheel effected.
50. 11. In apparatus for the purpose set forth a main wheel, a signal, a rock shaft, a crank on said shaft adapted to activate the signal, an arm on the rock shaft, and a projection on the main wheel to engage said arm whereby upon movement in one direction the signal will be activated and upon movement in the opposite direction the signal will be rendered inactive.
60. 12. In apparatus for the purpose set forth, a main wheel, a signal, a rock shaft, a crank on said shaft adapted to activate the signal, an arm on the rock shaft, a projection on the main wheel to engage said arm whereby upon movement in one direction the signal will be activated and upon movement in the opposite
- direction the signal will be rendered inactive, and a latch pivoted adjacent the arm to engage the same and support it in raised position and having its free end in the path of the projection to be engaged with and released from the arm thereby.
13. In apparatus for the purpose set forth, a main wheel, a signal, a rock shaft, a crank on said shaft adapted to activate the signal, an arm on the rock shaft, a projection on the main wheel to engage said arm whereby upon movement in one direction the signal will be activated and upon movement in the opposite direction the signal will be rendered inactive, a vibratory motor, a hook on the moving member of the motor, and an arm extending from the signal mechanism to engage said hook.
14. In apparatus for the purpose set forth, a main ratchet wheel having peripheral teeth and having a blank space at the location of one tooth.
15. In apparatus for the purpose set forth, a main wheel, means for rotating the same, a circular series of spaced studs on the rear side of the wheel, and an escapement lever having opposed staggered teeth engaging said studs.
- In testimony whereof I affix my signature.
